INVENTOR
GEORGE L. ELDRIDGE

BY

William Richards
ATTORNEY

UNITED STATES PATENT OFFICE.

GEORGE LEO ELDRIDGE, OF NEW BRUNSWICK, NEW JERSEY.

SIGN.

1,350,302.

Specification of Letters Patent. Patented Aug. 24, 1920.

Application filed November 7, 1919. Serial No. 336,449.

To all whom it may concern:

Be it known that I, GEORGE LEO ELDRIDGE, a citizen of the U. S., residing at New Brunswick, county of Middlesex, and State of New Jersey, have invented certain new and useful Improvements in Signs, of which the following is a specification.

This invention relates to display signs, and has for its object the provision of a sign which may be readily and simply constructed and attached to a wall or the like.

Briefly my invention consists of a frame having lugs invisible to an observer, for attaching it to a wall, and a panel of flexible material or metal so constructed that it may be quickly secured to said frame by folding certain parts back against shoulders on said frame, or simply by locking ears protruding from the panel about shoulders on the frame.

A further object of my invention is the provision of a neat sign which will be inexpensive to manufacture.

In the description below, characters of reference refer to similarly marked parts on the drawing.

Figure 1 is a front elevation of the complete sign.

Fig. 2 is a cross section on the plane 2-2 of Fig. 1.

Fig. 3 is a cross section on the plane 3-3 of Fig. 1.

Fig. 4 is a view of the sign cover before attachment, showing its one-piece construction.

Fig. 5 is a sectional view of a modification of my frame and panels.

1 represents a frame having lugs 2, projecting toward the interior thereof, for securing the frame to a wall. The frame is constructed of a cross section shown in Fig. 3, having shoulders 3 whose purpose will presently be described.

The panel 4 is made of flexible material, in one piece, having projections or ears 5 adapted to be folded around the eaves 6 of 45 the frame 1, and against said shoulders 3, as shown in Fig. 2. The remaining edges of the panel 4 are folded against the eaves 6, as shown in Fig. 3. Thus the panel, which carries the sign, is readily and securely attached to the frame, the two constituting a substantial and inexpensive sign.

Fig. 5 shows a sectional view of a modification of the frame and panel of Fig. 2, the shoulders 7 sloping in the reverse direction 55 of the shoulders 3. The panel 4 is bent in the form shown before it is placed on the frame, and is then locked on the frame by engagement of the ears 8 with the shoulders 7. Thus, this form of sign may be quickly 60 fixed to or removed from the frame, making it useful for advertising purposes when the advertisement is frequently changed.

Having thus described my invention, what I claim as new and desire to secure by Letters Patent, is:-

1. A sign comprising a frame having eaves whose rear edges are spaced forwardly from the rear edge of the body of the frame, and a panel therefor having ears adapted to 70 be folded around and behind said eaves and secured thereby.

2. A sign comprising a frame having shoulders thereon spaced forwardly from the rear edge of the frame, a panel, adapted to be locked thereon having ears bent substantially inward to engage behind said shoulders, and lugs on said frame extending toward the interior thereof to fasten the sign 75 to a wall.

In testimony whereof I have affixed my signature.

GEORGE LEO ELDRIDGE.
